UNITED STATES PATENT OFFICE.

CHARLES F. RAYDURE, OF WEST PHILADELPHIA, PENNSYLVANIA.

CONTACT-SHOE FOR THIRD-RAIL ELECTRIC CARS.

1,215,855.

Specification of Letters Patent. Patented Feb. 13, 1917.

Application filed April 24, 1916. Serial No. 93,153.

To all whom it may concern:

Be it known that I, CHARLES F. RAYDURE, a citizen of the United States, residing at West Philadelphia, in the county of Philadelphia and State of Pennsylvania, have invented certain new and useful Improvements in Contact-Shoes for Third-Rail Electric Cars, of which the following is a specification.

10 My present invention relates to certain novel improvements in the structural arrangement as well as operation of the contact shoe for third-rail electric-cars for which United States Letters Patent No. 15 1,169,865 were granted to me under date of February 1st, 1916.

In the present instance the contact shoe having the supporting member applied to the car truck-beam is provided with a 20 housed adjusting and take-up means and the contact shoe member straddles the said supporting member and the end pintles of the same are detachably mounted in upturned bearings of said supporting member; the arrangement being such that the 25 contact shoe member can be instantly parted from the supporting member without disturbing the same save removing the nut of the adjusting and take-up means and 30 loosening two nuts with which the electrical means are held in connection with the said shoe contact member for establishing a reliable working electrical condition thereof, the defined arrangement constituting what 35 is termed an overrun contact shoe for the third rail of an electric system.

The nature and scope of my present invention will be more fully understood from the following description taken in connection with the accompanying drawings forming part hereof, in which—

Figure 1 is a front elevational view of the complete contact shoe in a position adapted for use with the electric connections therewith to a fuse box shown in broken section and carried by the car truck-beam and the line cables therefrom through the car; the said view embodying as to the contact shoe-member with the supporting member structurally arranged for operation, the main features of my said invention.

Fig. 2 is a vertical sectional view on the line $x-x$, of Fig. 1; and

Fig. 3 is a view in perspective of the two members detached, showing the detail ar-

rangement of the overrun contact shoe member for application to its supporting member and housing adjusting or take-up means for the said contact shoe-member and operative from the outside and above the latter member in position.

Referring to the drawings a , is the contact shoe member, consisting of a rectangular shaped casting, as shown, having the 60 shoe or contact plate a^1 , as an integral part of the same. The rear of the said casting is formed with pintles a^2 and a^3 , and between them and extending in front thereof is a centrally located bridge piece a^4 , as 65 clearly shown in Fig. 3.

The supporting member b , is cast with a smooth surface back and sunken face and with a centrally located housing b^1 , and on each side is provided upturned bearings b^2 and b^3 , for engaging the pintles a^2 and a^3 of the contact shoe member. In the housing b^1 is mounted a flanged bolt b^5 carrying a helical or coiled spring thereon and when the contact shoe is caused to straddle by the bridge piece a^4 , the said housing b^1 , the upper end of the bolt b^5 , is passed therethrough and a nut b^6 , is applied to the same as clearly shown in Figs. 1 and 2, for adjustably positioning the contact shoe member a , in respect to the supporting member b , therewith. The arrangement is such that any wear or slack of the member a , can be 80 instantly compensated for to increase or decrease the tension under which it is held by either tightening or loosening the nut b^6 , on the spring-controlled bolt b^5 , mounted in the housing of the said supporting member b . This member is connected with the longitudinal truck-beam c , of the car by 85 means of bolts c^1 and c^2 , carrying as shown ribbed surface washers c^3 and c^4 . These bolts are capped by nuts c^5 and c^6 , to hold the same firmly or securely against movement in either direction of the member b , 90 as will be clearly understood from Fig. 1 of the drawings.

The electric connections d , fit a removable block d^1 , bolted to the recessed upper edge of the member b , as shown in Fig. 1. The cable d^2 , of the said connections, d , leads to a fuse box e , carried by the car truck-beam, and therefrom are lead line cables g^1 and g^2 , to and through the car to a source of supply, as clearly shown in Fig. 1. From 105 the block d^1 , cables d^3 and d^4 , lead to nuts a^7 and a^8 , located on both sides of the bridge 110

piece a^4 , as clearly shown in Figs. 1 and 3, for establishing reliable electrical connection of the contact shoe member with the supporting member and through the car to the source of electric supply.

The foregoing described contact shoe member in operative relationship with its supporting member carried by the car truck-beams is such, that as cast it can be employed without machining for necessary use. Further it can be readily adjusted or the tension under which it is held increased or decreased simply by manipulating the nut b^6 , of the spring-controlled bolt b^5 . Moreover, when necessary the overrun shoe contact member may be released by simply loosening the two nuts a^7 and a^8 , and removing the central nut b^6 of the bolt b^5 , and then lifting the said member a , by its pintles a^2 and a^3 , out of the bearings b^2 and b^3 , of the supporting member b , and without otherwise disturbing the latter member in its connection with the car truck-beam c , as will be apparent from Figs. 1 and 3 of the drawings.

Having thus described the nature and objects of my invention, what I claim as new and desire to secure by Letters Patent is:—

In an electric railway provided with a third rail conductor, a contact shoe for said conductor, comprising a supporting member arranged to be connected to the car truck-beam and having electrical connections, said member having upturned end bearings and a centrally located rectangular-shaped housing for a spring-controlled bolt mounted therein and an oblong flat face

overrun contact shoe-member arranged with a centrally located projecting rectangular-shaped bridge-piece and end pintles, said bridge-piece spanning the housing of said supporting member and the pintles thereof engaging the upturned bearings of said supporting member, the spring-controlled bolt held in the housing of said supporting member extending through the bridge-piece of said contact shoe-member, means detachably applied to said bolt above said bridge-piece to readily increase or decrease the tension of said contact and supporting members in respect to each other, and cables from the electrical connections of said supporting-member with said contact shoe-member, and positioned by nuts applied to bearings of said overrun contact shoe-member on opposite sides of the bridge-piece thereof, the arrangement being such that said contact shoe-member can be instantly parted from said supporting member without disturbing the same by simply removing the nut of said spring controlled bolt and loosening the nuts from the bearings of said contact shoe-member by which the electrical connections with said supporting-member are held in reliable working condition with said contact shoe-member.

In witness whereof, I have hereunto set my signature in the presence of the two subscribing witnesses.

CHARLES F. RAYDURE.
